MINING MACHINE

Original Filed July 6, 1925 2 Sheets-Sheet 2

UNITED STATES PATENT OFFICE.

CHARLES F. OSGOOD, OF CLAREMONT, NEW HAMPSHIRE, ASSIGNOR TO SULLIVAN MACHINERY COMPANY, A CORPORATION OF MASSACHUSETTS.

MINING MACHINE.

Application filed July 6, 1925, Serial No. 41,759. Renewed August 25, 1927.

My invention relates to mining machines and more particularly to feeding mechanism for a mining machine of the continuous cutter "low vein" type adapted to use with either the longwall or room and pillar system of mining.

A main object of my invention is to provide an improved continuous cutter "low vein" type mining machine having improved feeding means especially adapted to use with either the long wall or room and pillar system of mining. Another object of my invention is to provide an improved mining machine of extremely low and compact character especially adapted to use in mines having narrow veins of coal. Still another object of my invention is to provide a mining machine of the "low vein" type, wherein the height of the driving motor substantially determines the height of the machine, having a power driven feed operating member and a power driven controlling or take up member. A still further object of my invention is to provide a mining machine of the combined room and pillar and longwall "low vein" type having an improved arrangement of controlling and feeding parts whereby the movement of the machine during cutting in either system of mining is greatly facilitated. Yet another object of my invention is to provide an improved mining machine of the "low vein" invertible type adapted to use as either an undercutter or an overcutter. These and other objects of my invention will, however, hereinafter more fully appear.

In the preferred form of my invention the objects stated are achieved by providing a mining machine of the combined longwall and room and pillar continuous cutter "low vein" type having a plurality of power driven rope drums, one of which is for feeding the machine relatively to the coal face while the other is operative for controlling the position of the machine relative to the coal face, these drums being arranged in a novel location and driven from the driving motor in an improved manner. More specifically, a preferred embodiment of the invention may comprise an invertible machine frame slidable on either of two opposed surfaces on the mine bottom and preferably formed of a feed section, a central motor

section, and a cutter section, the latter having a projecting cutter bar which is pivotally mounted thereon and adapted to be locked in a plurality of operative positions relative thereto. The feeding mechanism preferably comprises a plurality of winding drums disposed on parallel longitudinally extending axes at one end of the machine frame and these drums are driven at either a fast or a slow speed and at any desired variants of such speeds under the control of a plurality of friction clutches. The drums may be connected to the terminal element of the feed transmission by means of separate friction clutches. Flexible feed cables may be attached to and wound upon the drums.

In the accompanying drawings, in which an illustrative embodiment of the invention is shown,

Fig. 1 is a view primarily in plan with parts broken away.

Fig. 2 is an elevation of the end of the machine remote from the cutting mechanism.

Fig. 3 is a central longitudinal vertical section on line 3—3 of Fig. 2 through the feeding mechanism, with parts shown in elevation.

Fig. 4 is a longitudinal vertical section on the line 4—4 of Fig. 2.

Fig. 5 is a fragmentary transverse vertical section on the line 5—5 of Fig. 3.

In the illustrative construction I have shown my invention embodied in an electric motor driven, flexibly fed mining machine which is adapted to cut either according to the room and pillar or the longwall system and which is adapted to slide upon its bottom 1 or its top 2 to insert a kerf either substantially at the level of the mine bottom or a substantial distance above the bottom. The machine comprises a frame generally designated 3 from which at one end a cutter bar 4 provided with cutting elements 5 circulating in a closed orbit extends, the bar 4 being pivotally mounted upon the end of the machine and adapted to be held in different positions with respect thereto by locking means 6. As illustrated, the bar may be held either in a position extending longitudinally of the machine frame 3 or at right angles to the frame and at either side thereof. In order to permit cutting according to the room and pillar method, a

guide sheave 7 having a mounting 8 whereby it may be bolted to the machine frame is provided adjacent the front end of the latter and this mounting can be shifted from side to side of the machine frame, depending upon the direction of cut desired. Feeding of the machine may be accomplished by either of two flexible feeding elements 9 or 10 each wound upon a feed operating member herein in the form of winding drums, the latter being respectively designated 11 and 12. During longwall cutting the feed operating member and flexible feeding member next to the face may preferably be employed, while during room and pillar cutting the feed operating member and the flexible feeding member at the advancing side of the machine may be used to effect feed, while the other feed operating member and flexible feeding member will be used to control the angular position of the machine relative to the coal face.

Referring more particularly to the machine, it will be noted that the same herein comprises three sections, a motor section 15, a feed section 16 and a cutter carrying section 17, the feed and cutter mechanism carrying sections being herein disposed at opposite ends of the motor section and rigidly connected to the latter at points above the bottom of the sections in such manner as to form a rigid and very low frame slideable on the mine bottom. It will be particularly noted that herein the upper and lower surfaces of the three sections 15, 16 and 17 are preferably disposed in common planes in such manner as to unite to form a single shoe adapted to permit free movement of the machine thereon over the mine bottom. The operative connections between the cutting mechanism and the motor 18 arranged within the motor section 15 may be of any suitable type and require no detailed illustration since they may follow the general construction illustrated in the copending application of Morris P. Holmes, Serial No. 619,839, filed Feb. 19, 1923 with appropriate modifications in view of the reversible character of the electric motor, or may take the form of the driving connections illustrated in the patent to Levin, 1,395,647, or any other suitable form.

The feeding mechanism is actuated by the end of the motor 18 remote from the cutting mechanism, said motor having an armature shaft 19 which carries at one end a driving pinion 20. This pinion is adapted to effect actuation through suitable fast and slow speed gearing of the feed operating members 11 and 12. First considering the fast feed mechanism more specifically, it will be noted that the pinion 20 meshes with a larger spur gear 32 suitably carried in a chamber 33 and mounted upon a shaft 34 which is journaled in suitable bearings 35. The gear

32 is in turn rigidly connected as by keying to a driving pinion 36 disposed coaxially therewith. As illustrated, the pinion 36 is meshed with a larger internal gear 37 having a hub 38 herein journaled on a suitable bearing sleeve 39, the sleeve being mounted on a clutch member 40 keyed, as at 41, to a longitudinally disposed main feed driving or transmission shaft 42 journaled at its opposite ends in suitable bearings 43 and 44 carried within the feed frame section. Moreover, it will be noted that the member 40 carries a series of friction disks 45 which are interleaved with a corresponding series of disks 46 carried by a sleeve on the internal gear 37. As shown, the sleeve on the internal gear 37 is also provided with a plurality of radially located longitudinally extending slots 47 receiving radial fingers 48 formed on an interlocking member 49 keyed to the hub of a pinion 50, the latter being freely rotatable on the shaft 42. Between these fingers 48 are friction clutch operating fingers 51 carried by a cylindrical member 52 disposed coaxially with the hub of the gear 50. These fingers 51 extend longitudinally into contact with one set of the friction disks 45, 46. As shown, the outer end of the shaft 42 has suitably secured thereto a spur pinion 53 which meshes with planetary speed reduction gears 54 (see Fig. 5) journaled on suitable ball bearings 55 carried by the longitudinally extending horizontal stub shafts 56 suitably secured to a spider member 57, the latter being journaled in ball bearings 58 suitably carried by the frame section. It will herein be observed that the planetary gears 54 are meshed with a stationary internal reaction gear 59 keyed, as at 60, to the frame section. Formed integral with the spider member 57 is a shaft portion 61 disposed coaxially with the main transmission shaft 42 and adjacent one end thereof. The shaft 61 has secured thereto as by a key 62, a spur pinion 63 herein forming the terminal element of the fast and slow feed transmission means which drives the feed operating members or drums 11 and 12 in an improved manner to be hereinafter described. It will thus be noted that the rotation of the armature shaft 19 may be transmitted through the improved fast speed mechanism to the terminal pinion 63 to drive the latter at a predetermined high or fast speed whenever the clutch controlling member 52 is operated to engage the clutch disks 45, 46. It will further be evident that such speed may be lowered at will by slipping the friction disks 45, 46.

Referring now specifically to the slow or cutting feed it will herein be observed that when the clutch controlling member 52 is inoperative and the clutch is released, power will still be transmitted through the interlocking member 49 to the pinion 50 which is

freely rotatable on the shaft 42. This pinion in turn meshes with a spur gear 64 disposed coaxially with the gear 32 and this gear has secured thereto and rotatable there-
 5 with a spur pinion 65 which meshes with a large internal gear 66 disposed coaxially with and rotatable on the shaft 42. This internal gear has secured thereto, as by a key 67, a spur pinion 68 which meshes with a
 10 spur gear 69 disposed coaxially with the gears 32 and 64 and this gear in turn drives a spur pinion 70 which meshes with an inter-
 15 nal larger gear 71 substantially similar to the internal gear 37 and disposed coaxially therewith. As illustrated, the internal gear 71 also houses a friction clutch substantially similar to the clutch heretofore described in connection with the clutch disks 45, 46 and this clutch includes interleaved clutch
 20 disks 72 and 73, certain of which are carried on a clutch member 74 keyed, as at 75, to the shaft 42 while others are carried by the sleeve formed integral with the internal gear 71. Moreover, a clutch retaining member
 25 76 is provided suitably secured to a spacing member 77 interposed between the bearing 44 and the clutch sleeve 74 and this retaining member 76 maintains the clutch disks 72, 73 in proper position. It will
 30 herein be noted that this retaining member 74 is similar to the member 49, but in this instance has no interlocking function and is only a disk retaining member. A cylindrical clutch operating member 78 surrounds
 35 the hub of the member 76 and is provided with longitudinally extending fingers 79 which engage certain of the friction disks 72, 73. As a result of this mechanism above de-
 40 scribed, although the clutch 45, 46 is disconnected, rotation will constantly be imparted through this slow feed mechanism so that when the clutch 72, 73 is connected the terminal gear 63 will be rotated at a slow or cutting speed in the same direction as the
 45 high or fast speed. Herein, it will also be evident that by slipping the friction disks 72, 73 this speed may also be reduced when desired. It will herein also be noted that suitable operating mechanism is provided
 50 for the clutch actuating members 52 and 78, which includes an operating member or handle 80 disposed at the feed end of the machine. Through suitable manipulation of this handle the fast and slow speed
 55 clutches may be selectively applied. Any suitable mechanism may be employed between the handle and the clutch loading members, but preferred devices are disclosed in the applications of Morris P. Holmes,
 60 Serial No. 619,839, supra, and in another application of the said Holmes, Serial No. 705,089, filed April 8, 1924.
 Operatively associated with the terminal pinion 63 of the fast and slow speed trans-
 65 mission means are larger spur gears 81 and 82 which are respectively secured as by keys
 66 to parallel longitudinally extending horizontal shafts 84 disposed parallel with and at opposite sides of the shaft 42 (see Fig. 4). Each of these shafts is journaled with
 70 in bearings 85 carried by a detachable frame section 86 forming a portion of the feed section 16. As the operative connections between the shafts 84 and the drums 11 and 12, respectively, are identical the description
 75 of one of the same will suffice for both. As illustrated, secured adjacent the outer end of the shaft 84 as by a key 87 is a clutch member 88 having a radially projecting flange portion 89 disposed within a bore 90
 80 formed within the feed operating member 12, the latter being journaled on bearings 91 carried by the frame section 86. A set of clutch disks 92 carried by the clutch member 88 are interleaved with a similar set of
 85 disks 93 carried by the feed drum 12. As shown the clutch member 88 is perforated, as at 93^a and through which perforations longitudinally extending clutch fingers 94 extend into contact with one of the clutch disks 92,
 90 93. These fingers are formed integral with a clutch operating member 95. Keyed, as at 96, to a reduced portion 97 of the shaft 84 is an externally threaded element 98
 95 which is threadedly engaged by a rotatable nut 99 having formed thereon a grasping portion herein in the form of a hand wheel 100. As shown, interposed between the nut 99 and the clutch operating member 95 is a ball thrust bearing 101 which permits relative rotation between the members 95 and 99.
 It will herein be noted that disposed at each side of the machine frame in longitudinally spaced relation are a plurality of guiding sheaves or rolls 102 rotatable on vertical
 100 axes and these rolls are adapted to guide the feed cables 9 and 10 during the different operations of the machine. It will further be noted that suitable elongated chambers 103 and 104 are formed at each side of the feed section 16 between which the fast and slow speed transmission means is disposed and in these chambers are housed suitable controller and resistance devices which are respectively indicated by the terms controller and resistance in Fig. 1 of the drawings.
 In the operation of my improved mining machine when utilized in accordance with longwall system of mining, the cable 10 may be extended along the side of the machine as indicated by dotted lines in Fig. 1 and attached in a suitable manner to the locking means 6 and the cutter bar swung about its pivot, at a slow or cutting speed under control of the friction clutch 72 and 73, from the dotted line position shown in Fig. 1 to the full line position, and the cutter bar then rigidly locked to the machine frame by the locking means 6. The cable 10 is then detached from the bar locking means and ex-
 110 115 120 125 130

tended around certain of the guide sheaves 102 to a point in advance of the machine frame, the free end of this cable being anchored in a suitable manner. The appropriate hand wheel 100 is then manipulated by the operator and the clutch 92 and 93 applied, thus causing the drum 12 to wind in the cable and the machine is fed at a cutting speed under the control of the handle 80 relative to the face of the coal. If it is desired to angle the machine during cutting, for instance if a sulphur ball is encountered, the cable 9 is extended in a suitable manner, for instance along the side of the machine frame, as indicated by dotted lines in Fig. 1, and around the guide sheave 7 to a suitable anchor. The friction clutch controlling the drum 11 may then be applied and the cable 9 wound in, thus causing the machine frame to be swung angularly relative to the face of the coal. It will be obvious that the bar may be locked at the opposite side of the machine frame and that the cables 9 and 10 may be extended in any desired manner to obtain any desired operation of the machine. During the operation of the machine in accordance with the room and pillar system of mining it will be noted that the cutter bar is locked in alignment with the longitudinal axis of the machine frame as indicated by dotted lines in Fig. 1. The cable 10 is then extended from the feed drum around certain of the guide rolls 102 and around the front guide sheave 7 laterally to a point in advance of the advancing side of the machine and suitably anchored in position. The receding cable 9 is extended from the other drum laterally of the machine frame to a point in the rear of the receding side of the machine and likewise suitably anchored in position. The operator then manipulates the handle 80 and the slow speed clutch 72 and 73 is loaded and then upon suitable manipulation of the hand wheels 100 the drums 11 and 12 are driven and the cables 9 and 10 governed in a suitable manner, the cable 10 feeding the machine while the cable 9 maintains a desired controlling tension on the rear end of the machine frame, thus preventing the cutter bar from being swung outwardly away from the kerf. It will herein be noted that if it is desired to cut in the opposite direction the cables 9 and 10 may be extended in an opposite manner, the guide sheave 7 transposed to the opposite side of the machine frame, and the cutter bits turned in their respective links. Other operations and advantages of my machine will be clearly apparent to those skilled in the art.

60 While I have in this application specifically described one form which my invention may assume in practice, it will be understood that this form of the same is shown for purposes of illustration and that the invention may be modified and embodied in

various other forms without departing from its spirit or the scope of the appended claims.

What I claim as new and desire to secure by Letters Patent is:

1. In a mining machine, a motor, and feeding means driven by said motor comprising a plurality of feed operating members rotatable on parallel longitudinally extending horizontal axes, and a friction clutch disposed within and coaxial with each of said members. 70
2. In a mining machine, a motor, and feeding means driven by said motor including variable speed transmission means including a terminal driven element, a plurality of feed drums rotatable on parallel axes, and means including friction clutches for connecting each drum to said terminal element. 80
3. In a mining machine, a motor, and feeding means driven by said motor including variable speed transmission mechanism including a plurality of friction clutches and a terminal driven element, a plurality of feed drums rotatable on parallel axes, and means including friction clutches for connecting said drums to said terminal element. 90
4. In a mining machine, a motor, and feeding means driven by said motor including variable speed transmission mechanism including a plurality of friction clutches and a terminal driven element, a plurality of feed drums rotatable on parallel longitudinally extending horizontal axes, and means including friction clutches for connecting said drums to said terminal element. 95
5. In a mining machine, a horizontal driving motor having a casing slidable on its bottom on the mine bottom, the height of the motor substantially determining the height of the motor substantially determining the height of the machine, and feeding means driven by said motor comprising a plurality of feed operating members rotatable on parallel longitudinally extending horizontal axes. 105
6. In a mining machine, a motor, cutting mechanism driven by one end of said motor, and feeding mechanism driven from the opposite end of said motor and comprising independently operable feed operating members rotatable on parallel axes. 115
7. In a mining machine, a motor, cutting mechanism driven by one end of said motor, and feeding mechanism driven from the opposite end of said motor and comprising independently operable feed operating members rotatable on parallel longitudinally extending horizontal axes. 120
8. In a mining machine, a motor having a horizontal longitudinally extending armature shaft, cutting mechanism driven from one end of said shaft, and feeding mechanism driven from the opposite end of said shaft and comprising a plurality of independent feed operating members rotatable on parallel axes. 125

pendently operable feed drums rotatable on parallel axes, and flexible feeding elements cooperating with said drums.

9. In a mining machine, a motor having a horizontal longitudinally extending armature shaft, cutting mechanism driven from one end of said shaft, and feeding mechanism driven from the opposite end of said shaft and comprising a plurality of independently operable feed drums rotatable on parallel longitudinally extending horizontal axes.

10. In a mining machine, a machine frame adapted to be supported on different parallel plane surfaces, a motor, the height of which substantially determines the height of the machine, and feeding means driven from said motor comprising a plurality of independently operable feed operating members.

20 11. In a mining machine, a machine frame adapted to be supported on different parallel plane surfaces during cutting, a horizontal motor having a casing slideable on its bottom on the mine bottom, the height of

25 which substantially determines the height of the machine, and feeding means driven from said motor comprising a plurality of feed operating members rotatable on parallel axes.

30 12. In a mining machine, a frame comprising a motor section, a feed section, and a cutting section, said motor section being interposed between said other sections, and feeding mechanism carried by said feed section and including a plurality of feed drums rotatable on parallel axes extending longitudinally of the machine.

35 13. In a mining machine, a motor, and feeding means driven thereby comprising variable speed transmission mechanism including coaxial driving elements, and a plurality of independently operable feed drums rotatable on spaced longitudinally extending axes parallel with the axes of said driving element.

45 14. In a mining machine, a motor including a horizontal longitudinally extending armature shaft, variable speed transmission means including clutches disposed coaxially with said shaft, and feed operating members rotatable on axes parallel with the axis of said shaft and adapted to cooperate with flexible feeding means.

55 15. In a mining machine, a horizontal motor having a casing slideable on its bottom on the mine bottom, the height of which determines the height of the machine, cutting mechanism driven by said motor, and feeding mechanism driven by said motor and carried by the end of the machine opposite from said cutting mechanism and including a plurality of feed drums rotatable on axes extending longitudinally of the machine.

60 16. In a mining machine, a motor the height of which determines the height of

the machine, cutting mechanism driven by said motor, and feeding mechanism driven by said motor and carried by the end of the machine opposite from said cutting mechanism and including a plurality of feed drums rotatable on parallel longitudinally extending horizontal axes. 70

17. In a mining machine, a motor, and feeding mechanism driven by said motor comprising separate coaxial fast and slow speed clutches, a driven terminal element disposed with its axis in the central longitudinal vertical plane of the machine, and feed drums driven by said element rotatable on parallel axes. 75

18. In a mining machine, a motor, and feeding mechanism driven by said motor comprising coaxial fast and slow speed clutches, a driven terminal element disposed with its axis in the central longitudinal vertical plane of the machine, feed drums driven by said element rotatable on parallel axes, and a friction clutch disposed coaxially with each drum. 85

19. In a mining machine, a motor, and feeding means driven by said motor comprising fast and slow speed transmission means including planetary gearing whose elements rotate on axes extending longitudinally of the machine, a terminal element driven thereby, and a plurality of feed drums driven by said terminal element rotatable on parallel axes in a common zone transverse to the drum axes. 90

20. In a mining machine, a motor and feeding means driven by said motor comprising fast and slow speed transmission means including planetary gearing whose elements rotate on axes extending longitudinally of the machine, a terminal element driven thereby, and a plurality of feed drums driven by said terminal element rotatable on parallel longitudinally extending horizontal axes. 105

21. In a mining machine, a motor and feeding means driven by said motor including variable speed transmission means including planetary gearing, a terminal element driven thereby, a plurality of feed drums driven by said terminal element and rotatable on parallel axes, and a friction clutch disposed coaxially with each of said drums. 110

22. In a mining machine, a motor, cutting mechanism driven from one end of said motor and including a pivoted cutter bar, and feeding mechanism driven from the opposite end of said motor and comprising feed operating members adapted to cooperate with flexible feeding means, said members being rotatable on parallel axes disposed substantially parallel with the coal face during cutting. 120

23. In a mining machine, a machine frame having top and bottom parallel plane sur- 130

faces on which the machine is adapted to be selectively supported during cutting, a horizontal motor within said frame, the height of the motor substantially determining the height of the machine cutting mechanism driven by said motor, and feeding means for the machine driven by said motor comprising independently operable feed operating members adapted to cooperate with flexible feeding means, said feed operating members being adapted to feed said machine while the latter is supported on either the top or bottom surface of said frame.

24. In a mining machine, a machine frame having top and bottom parallel plane surfaces on which the machine is adapted to be selectively supported during cutting, a motor within said frame, cutting mechanism driven by said motor, and feeding means for the machine driven by said motor including independently operable feed operating members rotatable on horizontal axes disposed midway between the top and bottom surfaces of the machine frame, said members being adapted to feed said machine while supported on either the top or bottom surface of said frame.

25. In a mining machine, a horizontal motor having a casing slidable on its bottom on the mine bottom, the height of said motor substantially determining the height of the machine, cutting mechanism driven from one end of said motor, and feeding means for the machine driven from the opposite end of said motor and including independently operable feed operating members adapted to cooperate with flexible feeding means, said feed operating members being rotatable on parallel axes.

26. In a mining machine, a horizontal motor having a casing slidable on its bottom on the mine bottom, the height of the motor substantially determining the height of the machine, cutting mechanism driven by said motor, and feeding means for the machine driven by said motor comprising a plurality of feed operating members rotatable on parallel axes and disposed in a common zone transverse to said axes.

27. In a mining machine, a motor, plural speed transmission means driven thereby including planetary gearing, a plurality of feed operating and controlling members rotating on parallel axes lying in vertical planes extending longitudinally of the machine, and means for connecting said members to said gearing including friction clutches coaxial with said members.

28. In a mining machine, a motor having a casing slidable on its bottom on the mine bottom, the height of the motor substantially determining the height of the machine, and feeding means driven by said motor including a plurality of independently operable feed operating and controlling members

rotatable on parallel axes lying in vertical planes extending longitudinally of the machine.

29. In a mining machine, a motor, plural speed transmission means driven thereby and including planetary gearing disposed with its axis of orbital movement horizontally and extending longitudinally of the machine, a plurality of feed operating and controlling members rotatable on parallel axes extending longitudinally of the machine and equidistant from said axis of orbital movement, and means for connecting said members to said gearing.

30. In a mining machine, a machine frame slidable directly on its bottom on the mine bottom during cutting, a horizontal motor in said frame having its axis extending longitudinally of the machine, cutting mechanism driven from one end of said motor including a horizontally swingable cutter bar, and feeding mechanism driven from the opposite end of said motor including a feed operating member and a take-up member each adapted to cooperate with flexible feeding means, said members being disposed wholly within the lateral limits of said frame.

31. In a mining machine, a motor having a casing slidable directly on its bottom on the mine bottom during cutting, the height of the motor substantially determining the height of the machine, said motor having its armature shaft disposed horizontally and longitudinally of the machine substantially midway between the top and bottom of said casing, cutting mechanism driven from one end of said motor, and feeding mechanism driven from the opposite end of said motor and including a feed operating member and a take up member each adapted to cooperate with flexible feeding means.

32. In a mining machine, a machine frame having top and bottom parallel plane surfaces on which the machine is adapted to be selectively supported during cutting, a horizontal motor in said frame having its axis extending longitudinally thereof, cutting mechanism driven from one end of said motor including a horizontally swingable cutter bar, and feeding means driven from the opposite end of said motor including a feed operating member and a take up member each adapted to cooperate with flexible feeding means.

33. In a combined room and pillar and longwall mining machine, an elongated machine frame slidable on its bottom on the mine bottom during cutting and comprising a cutting section, a motor section and a feed section, said motor section being interposed between said cutting and feed sections, a horizontal motor disposed in said motor section and having its power shaft extending longitudinally of the machine, cutting mech-

anism driven from one end of said motor and including a horizontally swingable cutter bar pivoted on said cutting section, said bar being disposable at opposite sides of the machine and lengthwise of the machine during different operations thereof, and feeding mechanism driven from the opposite

end of said motor including a feed operating member and a take up member carried by said feed section, said members each being adapted to cooperate with flexible feeding means. 10

In testimony whereof I affix my signature.

CHARLES F. OSGOOD.

CERTIFICATE OF CORRECTION.

Patent No. 1,664,387.

Granted March 27, 1928, to

CHARLES F. OSGOOD.

It is hereby certified that error appears in the printed specification of the above numbered patent requiring correction as follows: Page 4, lines 106 and 107, claim 5, strike out the words "height of the motor substantially determining the"; page 5, line 45, claim 13, for the word "element" read "elements"; page 6, line 5, claim 23, after the word "machine" insert a comma; and that the said Letters Patent should be read with these corrections therein that the same may conform to the record of the case in the Patent Office.

Signed and sealed this 29th day of May, A. D. 1928.

(Seal)

M. J. Moore,
Acting Commissioner of Patents.
